UNITED STATES PATENT OFFICE.

RALPH O. HOLT, OF PRINCESS BAY, NEW YORK, ASSIGNOR OF FORTY PER CENT TO HENRY C. FAHRENKRUG, OF BROOKLYN, NEW YORK.

AUTOMATIC STOPPING DEVICE FOR PRINTING PRESSES AND PAPER-FOLDING MACHINES.

Application filed December 22, 1926, Serial No. 156,441. Renewed February 2, 1929.

This invention relates generally to printing presses and folding machines, and has more particular reference to an automatic stop device therefor.

5 The invention has for an object the provision of an improved automatic stop device for printing and folding machines which will act to stop the machine if the sheets of paper being printed or folded jam, or do not feed properly.

For further comprehension of the invention, and of the objects and advantages thereof, reference will be had to the following description and accompanying drawing, and 15 to the appended claims in which the various novel features of the invention are more particularly set forth.

Referring to the drawing forming a material part of this disclosure:

20 Fig. 1 is a side elevational view of a printing press with the invention device applied thereto.

Fig. 2 is a fragmentary enlarged view of a portion of the device shown in Fig. 1.

25 Fig. 3 is a plan view thereof.

Fig. 4 is a fragmentary enlarged view of another portion of the device shown in Fig. 1.

Fig. 5 is a vertical sectional view taken on the line 5—5 of Fig. 4.

30 Fig. 6 is an enlarged view of another portion of the device shown in Fig. 1, namely the switch box with its cover opened, disclosing the interior thereof.

Fig. 7 is a vertical sectional view taken on 25 the line 7—7 of Fig. 6, when the circuit breaker is in open position.

Fig. 8 is a schematic wiring diagram of the device.

The reference numeral 10 indicates the 40 frame of a printing machine, having a type frame 11 slidably mounted thereon, and moved backwards and forwards by an arm 12 pivoted intermediate of its ends to the frame 10, as at 13, and connected at its upper end 45 to the type frame 11. Tension spring 14 is connected between the lower end of the arm 12 and the frame 10. Mounted on the frame 10 is an electric motor 15 connected by belt 16 guided by idler 17, to a wheel 18 having 50 coaxially secured thereto a gear 19, meshing with another gear 20 provided with an eccentrically mounted connecting rod 21 engaged at one end to the arm 12 to oscillate the arm obtaining the forward and backward motion

of the type frame 11. Suitably mounted on 55 top of the frame 10 is a cylinder 22 coacting with the type frame to print the sheets of paper 23 passed by suitable feeding apparatus from 23' to 23^a. The sheets at 23' are on a table 24 vertically slidably mounted in 60 frame 25. Means not shown on the drawing cause the table 24 to rise as necessary to feed the sheets to a feeding mechanism 26 not shown in detail. It is this feeding mechanism that passes the sheets individually from 65 23' to between the cylinder 22 and the type frame, and thereafter to 23^a. The ends 27 of inking rolls are illustrated, but the detail operation thereof is not shown.

The feeding mechanism 26 tilts upwardly 70 toward the delivery table and will feed only a predetermined number of sheets to the said table as will hereafter be pointed out. The said feeding mechanism is formed with several conveying belts 28 which carry the sheets 23. 75 Beneath these belts a rod 29 is supported, and electrically grounded to the frame 10 as indicated at 30. Suitably supported to the frame 10 is a bracket 31 of insulation material, having a projecting pindle pin 32 electrically connected to binding post 33, and pivotally supporting a spring metal contact arm 34 intermediate of its length. This contact arm is of such length and shape that one end is engageable with rod 29, normally urged into 80 engagement by the weight of an attached projecting stud 35, and weights applied thereon, not shown on the drawing, while the other end of the contact arm 34 contacts with a stationary contact arm 36 supported by 85 bracket 31 and electrically connected to terminal 37. If a sheet 23 is passing over rod 29 the contact arm 34 is insulated therefrom, otherwise it contacts therewith. The contact arm 34 makes contact with the stationary 90 arm 36 every time a sheet passes between the said arm 34 and the rod 29 but the electrical circuit is not completed as will hereinafter be explained.

Pivotally connected to the arm 12 is one 100 end of a link 38, pivotally connected at its other end to a lever 39 projecting from roller 40 on shaft 41 mounted in frame 25. Screw 42 also projects from the roller 40, and is electrically connected thereto, the roller being grounded indicated at 43 to the frame 25 which is electrically connected to frame 10 by the feeding mechanism 26. Mounted to the 105

frame 25 is a bracket 44 having a top projecting contact arm 45 in the path of motion of screw 42, and connected to terminal 46 which is connected to terminal 47 by link 48. 5 A contact arm 49 is reinforced by arm 50, and electrically connected to terminal 47 by wire 51^a, while another contact arm 51 coactable with contact arm 49, is connected to terminal 52 by wire 53. Normally contact arms 10 49, 51 are disengaged from each other, but may be engaged by the action of screw 42 abutting against the contact arm 50. The link 38, lever 39, and screw 42 are so arranged that when a natural space between the sheets 15 23 passing over rod 29 occurs, and the contact arm 34 contacts with the rod 29, the screw 42 will be between 45 and 50 but not connecting with either one of these. As the type frame and its actuating arm 12 which operates the roller 40 and setscrew 42 will at this time be somewhere between the two extremes of its movement, contact between the screw 42 and either the arm 45 or arm 50 is only possible at such extreme points. As the type 20 frame 12 moves to the right, the screw 42 moves to about 50, which causes arms 49 and 25 51 to engage. The arm 50 is insulated from the arm 49 by the insulation members 54.

Mounted on the frame 10 is a switch box 55 30 having a cover 56. Fastened to the bottom of the box 55 is an insulation block 57 supporting a pair of fuses 58, each fuse being connected at one end to terminals 59, 60, and at the other end to a circuit breaker comprising 35 pivoted mounted knives 61, 62, engageable with knife slots 63, 64 connected to terminals 65, 66. Connecting the knives 61, 62 is a bridge 67 of insulation material. A link 68 is pivotally engaged to the bridge 67, and is formed with an elongated aperture 69 at its front end. Engaged in this aperture 69 is a crank lever 70 pivoted as at 71 in the sides of the box 55, and formed at one end with a projecting handle 72. Normally holding the 40 crank 70 in the position shown in Fig. 7, that is with the knives 61, 62, disengaged from slots 63, 64, is a tension spring 73 acting between 70 and the box 55. Another tension spring 74 acts between the crank 70 and the 45 bridge 67 to normally keep the crank 70 in that end of aperture 69 as shown in Fig. 7. A catch 75 projects from the bridge 67, and is engageable with a complementary catch 76 on an armature 76^a pivoted at 76^b. When 50 these catches engage each other, as shown in Fig. 6 the knives 61, 62, engage the knife slots 63, 64. By turning the handle 72 in the proper direction, the crank 70 presses against the end of slot 69 of link 68, forcing the bridge 67 into such position that the knives 55 engage the knife slots, and the catches engage each other holding the bridge in this position. Mounted above catch 76 is solenoid 77.

The terminal 33 is connected to the positive 60 terminal of battery 78 and the negative ter-

65 minal of the battery is connected to the single pole switch 79 fastened on the side of box 55. From switch 79 a wire 80 leads to terminal 81 of a contact arm 82 engageable by another contact arm 83 having a terminal 84. A lead 70 connects terminal 84 with the solenoid 77. Projecting from bridge 67 is a screw 85 adapted to abut arm 82 to engage arm 83 when the bridge is in closed position, that is when the knives 61, 62, engage the knife slots 75 63, 64. The other end of the solenoid winding 77 is connected to terminal 46, and lead 85^a connects terminals 52 and 37. A double pole switch 86 is fastened on the side of the 80 box 55. This switch 86 is connected to terminals 59, 60 and some source of power, not shown on the drawing. Terminals 65, 66 are connected to the motor 15, not shown on the drawing. The operation of the device is as 85 follows:

Handle 72 is turned to engage the catches 75, 76, closing the knives 61, 62 and also contact arms 82, 83. Next switch 79 is opened, and thereafter switch 86 is closed which causes motor 15 to operate, and the printing 90 machine is set in motion. Next the feeding mechanism is set in motion by certain control levers not shown on the drawing. The switch 79 is closed. Each passing sheet of paper 23 insulates bar 29 from arm 34, but there is a certain space between the passing sheets and during this period, one end of 34 contacts with 29, and as before explained simultaneously screw 42 is passing between 45 and 50 but connecting with neither.

If anything should happen to the feeding mechanism and the sheets 23 no longer pass 29, then contact arm 34 will continuously contact with 29, and the next time screw 42 contacts with arm 45 a closed circuit will exist between grounds 30, 43, bar 29, arm 34, terminal 33, battery 78, switch 79, contacts 82, 83, the solenoid 77, terminal 46 and arm 45. The solenoid will be energized, lifting armature 76^a and disengaging catch 76, and catch 75, and permitting spring 73 to swing bridge 67 to open position, which opens knives 61, 62 from the knife slots 63, 64, breaking the circuit of motor 15 and stopping the printing machine. As the bridge opens, the screw 85 releases the arms 82, 83, allowing them to 115 break the circuit containing battery 78, so that the battery will not be needlessly exhausted.

If for any reason the sheet was to remain 120 between the contact arm 34 and the rod 29 long enough for the arm 12 to reach the extreme of its rearward movement, then the setscrew 42 would cause arms 49 and 51 to contact, thus closing the circuit through arm 34, arm 36, lead 85^a, terminal 52, arm 51, arm 49, terminal 47, lead 48, terminal 46 to solenoid 77, arms 82 and 83, lead 80, switch 49, battery 78, terminal 33.

While I have illustrated and described my 130

invention with some degree of particularity, I realize that in practice various alterations therein may be made. I therefore reserve the right and privilege of changing the form of 5 the details of construction or otherwise altering the relation of the correlated parts without departing from the spirit or the scope of the appended claims.

Having thus described my invention, what 10 I claim as new and desire to secure by United States Letters Patent is:—

1. An automatic stop device for printing machines and other machines having a paper feeding device, comprising a contact rod, a 15 pivoted contact arm, one end of the arm being engageable with the rod, a stationary contact arm engageable with the other end of the pivoted contact arm, the rod and pivoted arm being adapted to allow feed paper to 20 pass therebetween, and the feeding paper to contact the pivoted arm with the stationary one, circuit closing means, a circuit breaker actuated by the said circuit closing means for stopping the machine if feed paper is 25 not between the rod and pivoted arm, means for preventing the action of said circuit closing means at such time when naturally feed paper does not pass between the rod and pivoted arm, and means permitting the operation 30 of the said circuit closing means when the pivoted and stationary arms contact.
2. A stop mechanism for a paper sheet feeding machine having an oscillating member in cooperative relation with the feeding mechanism, the said stop mechanism comprising a roller rotatably mounted on the machine, an extension on the roller, means for connecting the roller to the oscillating member, a plurality of electrical circuit makers operated by 35 the extension, a circuit maker and breaker operated by the sheet, and a circuit breaker operated by the aforementioned circuit makers and breaker to stop the machine when there is an interruption in the feed of the 40 paper.
3. A stop mechanism for a paper sheet feeding machine having an oscillating member in cooperative relation with the feeding mechanism, the said stop mechanism comprising a roller rotatably mounted on the machine, an extension on the roller, means for connecting the roller to the oscillating member, a plurality of electrical circuit makers operated by the extension, a circuit maker and breaker operated by the sheet, and a circuit breaker operated by the aforementioned circuit 45 makers and breaker to stop the machine when the paper is being jammed.
4. A stop mechanism for a paper sheet feeding machine having an oscillating mem-

ber in cooperative relation with the feeding mechanism, means for stopping the machine if there is an interruption in the feeding of the paper, said means including a rod electrically grounded, an arm pivotally mounted on the machine normally in the path of the paper and in contact with the rod when there is no paper feeding, several circuit makers operatively connected to the oscillating member, and a circuit breaker adapted to 70 break the circuit when the oscillating member actuates the aforementioned circuit makers while there is no paper feeding and the pivoted arm is in contact with the rod.

5. A stop mechanism for a paper sheet 75 feeding machine having an oscillating member in cooperative relation with the feeding mechanism, means for stopping the machine when the paper is jamming, said means including a rod electrically grounded, an arm pivoted intermediate its ends, a fixed contact arm in engagement with the pivoted arm when a sheet of paper is jamming between the said arm and rod; a plurality of circuit makers operated by the oscillating member and a circuit breaker energized by the circuit makers to stop the machine when the paper is in the above mentioned position.

6. A stop device for printing and other paper feeding machines having an oscillating member, the said stop device comprising an electrically grounded rod, a pivoted arm actuated by a sheet of paper passing between the rod and arm, a second contact arm in engagement with the pivoted arm when there is a sheet of paper between the rod and said pivoted arm, circuit closing means operated by the oscillating member, a circuit breaker actuated by the circuit closing means to stop the machine when the paper is jamming or the feeding thereof has ceased and means to prevent the stopping of the machine when the paper is feeding properly.

7. A stop device for printing and other paper feeding machines having an oscillating member, the said stop device comprising an electrically grounded rod, a pivoted arm actuated by a sheet of paper passing between the rod and arm, a second contact arm in engagement with the pivoted arm when there is a sheet of paper between the rod and said pivoted arm, circuit closing means operated by the oscillating member, and a circuit breaker actuated by the circuit closing means to stop the machine when the paper is jamming or the feeding thereof has ceased.

In testimony whereof I have affixed my signature.

RALPH O. HOLT.
